UNITED STATES PATENT OFFICE.

WILLIAM H. VOSBURGH, JR., OF TROY, NEW YORK.

COLORED-FIRE TORCH.

SPECIFICATION forming part of Letters Patent No. 431,827, dated July 8, 1890.

Application filed January 21, 1890. Serial No. 337,597. (No model.)

To all whom it may concern:

Be it known that I, WILLIAM H. VOSBURGH, Jr., of the city of Troy, county of Rensselaer, and State of New York, have invented a new 5 and useful Improvement in Colored-Fire Torches, of which the following is a specification.

My invention relates to an improvement in that class of colored-fire torches which have 10 a case for containing colored fire and are provided with a wooden handle by which they are grasped and held while the composition is burning. As this class of torches are usually made they are lighted from the end by a 15 match or other igniting means not connected with the torch. When carried in processions, there is difficulty in lighting them, particularly if the wind is blowing, and it is to combine with the torch a means for lighting it 20 that is the object of my invention. Thus provided, on the order from the officer in command of a procession or from a given signal all the torches in line can be lighted at one time, and so as to produce instantaneous illumination. 25

Accompanying this specification to form a part of it there is a sheet of drawings containing four figures illustrating my invention, with the same designation of parts by letter 30 reference used in all of them.

Of the illustrations, Figure 1 is a side elevation of my improved torch. Fig. 2 is a section taken longitudinally and centrally through the torch. Fig. 3 is a plan view of a 35 paper disk that is inserted in the end of the case, said disk being provided with an ignition composition upon one edge. Fig. 4 shows the same disk shown at Fig. 3, but with a modified manner of arranging the ignition 40 composition.

The several parts of the torch thus illustrated, and as well as those containing my improvement, are designated by letter reference, and the function of the parts is de- 45 scribed as follows:

The letter C designates the case, which is made of paper or thin straw-board; H, the handle, down over which the lower end of the case extends for securing the latter to the 50 handle.

The letter A' designates the composition for

burning, which is arranged within the case, and A² some quick composition arranged on top of the burning composition, this quick composition having gunpowder mixed therewith, or other like material, which will ignite readily and expand with enough force to blow out the disk D, arranged over said quick composition. 55

The letter I designates an ignition composition that is lighted by friction, which is arranged upon one edge of the disk, as shown at Fig. 3, or by placing a match M, having upon its end ignition composition I, which match is secured to the top or bottom of the 65 disk D, with the latter cut away or recessed at R, as shown at Fig. 4.

The letter C² designates a cap arranged on the upper end of the case C.

The letter S designates a strip of paper, one 70 end of which extends down into the case, as indicated at S², with its entered end loosely therein and at one side of the interior thereof, with the outer end of the paper strip extended down on the exterior of the case, and 75 which is, preferably at its lower outer end, pasted to the exterior of the case at P. This strip of paper, where within the case, and as indicated at F, is on its inner face coated with a sand-paper finish, and so that when the 80 outer end of the strip is drawn suddenly from the case the sand-paper or friction face will engage with the ignition composition I to fire the same and at the same time explode the quick composition A², and thus ignite the colored-fire composition A'. For the friction 85 composition any of the well-known match compounds may be used.

As thus made, by pulling out the paper strips simultaneously the colored-fire torches 90 of a long procession can be lighted up and without difficulty.

Having thus described my invention, what I claim, and desire to secure by Letters Patent, is—

1. The combination, with a colored-fire torch provided with a case to contain the burning composition, of a quick composition arranged within the case on top of the burning composition, a disk arranged on top of the 100 quick composition, a friction lighting compound arranged on the edge of said disk, and

a friction-strip having a rough face that will engage with said friction lighting compound when said friction-strip is drawn from out the case, substantially in the manner as and for 5 the purposes set forth.

2. As a new article of manufacture, a torch for burning colored fire, in which the latter is lighted by means of a friction ignition compound arranged within the case, and a strip 10 of paper having a rough surface that engages

with said friction ignition compound when said strip is drawn from out the case, substantially as herein set forth.

Signed at Troy, New York, this 4th day of November, 1889.

WM. H. VOSBURGH, JR.
